UNITED STATES PATENT OFFICE.

ELWOOD B. AYRES, OF PHILADELPHIA, PENNSYLVANIA, ASSIGNOR TO THE PHILADELPHIA TEXTILE MACHINERY COMPANY, OF PHILADELPHIA, PENNSYLVANIA, A CORPORATION OF PENNSYLVANIA.

DRIER.

1,388,790.

Specification of Letters Patent. Patented Aug. 23, 1921.

Application filed September 23, 1919. Serial No. 325,714.

To all whom it may concern:

Be it known that I, ELWOOD B. AYRES, a citizen of the United States, residing in Philadelphia, Pennsylvania, have invented 5 certain improvements in Driers, of which the following is a specification.

My invention relates to certain improvements in driers, especially adapted for drying skins, and like objects which have to 10 be fastened to a board or a frame, and which are carried through the drying chamber at a given speed so that the skins will be dried when they leave the machine.

One object of the invention is to provide 15 a machine in which detachable boards can be readily mounted in position and located in the carriers of the machine.

A further object of the invention is to provide a drier in which one set of boards 20 travels through the machine in one direction and another set of boards travels through the machine in the opposite direction.

The invention also relates to certain details which will be fully described herein- 25 after.

In the accompanying drawings:

Figure 1 is a side view illustrating my invention;

Fig. 2 is a plan view;

Fig. 3 is an enlarged end view;

Fig. 4 is an enlarged side view of one end of the drier;

Fig. 5 is a perspective view illustrating the construction of the frame and the means 35 for holding the boards; and

Fig. 6 is a view illustrating a modification.

1 is a casing having two chambers 2, 2^a, separated, in the present instance, by a heating chamber 3, in which are coils of pipe, or other suitable heating devices. Directly above the heating chamber is a circulating chamber 4. There is an opening in the partition between the two chambers and in this 45 opening are the circulating fans 5 driven in any suitable manner. There are the usual openings in the upper and lower portions of the vertical partitions 6 separating the central heating chamber from the drying chambers so that air will circulate freely 50 through these several chambers.

7, 7 are conveyer chains adapted to travel on rails 9 at each side of the drying chambers 2^a. These chains pass around sprocket

wheels 8, 8^a at each end of the machine. 55 The wheels 8 are mounted on a shaft driven from any suitable source of power, one set of chains traveling in one direction in one drying chamber, and the other traveling in the opposite direction in the other drying chamber, Fig. 2. Pivotaly mounted at 11, at each end of the structure, is a frame 10, which is supported on rollers 12 so that it can be swung in front of one drying chamber, or the other, as desired. 60

13, 13 are the drying boards on which the skins are tacked, or otherwise secured. These boards may be plain boards, or may be made in accordance with the construction illustrated in the application for patent filed 70 by me even date herewith, Serial No. 325,715, in which two skins can be attached to each board, one on one side of the board and the other on the opposite side thereof. Means are provided for stretching these 75 skins on the boards.

In some instances, the frame 10 may be supported entirely by the hinge and the arms which carry the rollers 12 may be dispensed with, as shown in Fig. 6. On the frame 10 80 are sockets 14 to receive the pivot pins 15 projecting from the boards 13. The pivots are slightly above the center, as shown, so that the boards will remain in a vertical position, but can be readily turned to a horizontal position when it is desired to attach the skins to the boards, after the boards have been mounted in the frame. 85

It will be noticed that each frame has pins 16, one at each side of the pivots 15, and rods 90 17 are pivoted to the frame 10 at 18 and are arranged to engage the pins 16 so as to hold the frame in a horizontal position, as illustrated in Figs. 3 and 5. Suitable doors may be provided for the drying chambers, if 95 found desirable.

Where drying boards are used of a size to close the openings in the drying chambers, then these boards prevent the heated air in circulation within the chambers from 100 escaping to any considerable extent at the ends of the drying chambers.

The operation is as follows: The skins to be dried are tacked to one side of the board, when in the horizontal position, as shown in 105 Fig. 3. The board is then turned on its pivot, so that the other surface of the board will be uppermost, after which another skin

is attached to that side of the board. The board is then swung to the vertical position, as shown in Fig. 1, and the frame is turned on its pivot so as to present the board to the feed end of the chamber 2. The mechanism is so arranged that the pivot of the board can be transferred onto the endless chain 7, which travels slowly through the drying chamber. By feeding one board after another into the chamber, the entire chamber is filled. These vertical boards are spaced a sufficient distance apart to allow the air to circulate freely through the spaces. The length of the chamber is such that the skin 15 will be properly dried when it reaches the delivery end. At the delivery end the board is transferred onto another pivoted frame 10, similar to that at the opposite end of the machine and the frame is moved to the central position and the skins are removed from the board and other skins secured thereto. The board may be detached and another board placed in position with other skins attached thereto.

20 The frame, with the skins tacked thereon, is moved in front of the chamber 2^a and is transferred to the conveyer 7 in this chamber and traversed through the chamber in the same manner as the boards are traversed 30 through the chamber 2.

It will be seen that by the use of a drying apparatus in which there are two drying chambers a number of boards, with the skins thereon, can be traversed in one direction, 35 while the other boards can be traversed in the opposite direction. The same pivoted frame that places a board in position at the feed end of one chamber can be used to remove the board at the discharge end 40 of the other chamber.

I claim:

1. The combination of a drier having two drying chambers; means for circulating air through the chambers; a pivoted frame at 45 one end of the drier arranged to carry boards on which skins, or other objects, are secured, and so arranged that it can be swung in front of either drying chamber.

2. The combination of a drier having two 50 compartments; means for conveying material in each compartment; a pivoted frame at each end of the drier for carrying material to be dried in a position to transfer material from the frame to the conveying 55 means at one chamber and so arranged as to swing in position to receive dried material from the other chamber.

3. The combination of a drier having two 60 longitudinal drying chambers; a heating chamber located between the drying chambers; means for circulating air through the heating chamber and the drying chambers; conveyers in each chamber, one conveyer moving in one direction and the other in 65 the opposite direction; a frame pivoted in

a central position at each end of the drier and arranged to swing in front of either drying chamber so as to carry material to the feed end of one chamber and to receive material from the feed end of another chamber. 70

4. The combination of a drier having two longitudinal drying chambers; a heating chamber located between the drying chambers; a circulating chamber between the drying chambers; a series of fans causing a circulation of air through the several chambers; a conveyer chain at each side of each chamber; rails supporting the chains; a series of boards carried by the chains 80 through the drying chambers; means at each end of the conveyer for carrying boards into position at the feed end of one conveyer and to receive the boards from the discharge end of the other chamber. 85

5. The combination of a drier having two compartments; conveying means in each compartment, one traveling in one direction and the other traveling in the opposite direction, a pivoted frame arranged to swing in front of either compartment and having pivoted supports; boards having pivot pins arranged to be mounted on said supports so that the boards can be transferred into one chamber and removed from the other 95 chamber.

6. The combination of a drier having two drying chambers; conveyers in each chamber, one conveyer arranged to traverse material in one direction and the other conveyer arranged to traverse material in the opposite direction; a pivoted frame at each end of the drier arranged to swing in position in line with either drying chamber; drying boards detachably and pivotally 100 mounted on the frame; means for holding the boards in a horizontal position in order to allow skins to be tacked thereon so that boards, with skins thereon, can be shifted into position to be transferred to the feed 110 end of one drying chamber and the frame can be swung into position to receive boards from the discharge end of the other drying chamber. 105

7. The combination of a drier having two 115 drying chambers; means for circulating air in said chambers; a conveyer in each drying chamber; and means, at one end of the drier, for transferring a carrier for material to be dried from one chamber to the other. 120

8. The combination of a drier having two longitudinal drying chambers; means for circulating air in said chambers; a conveyer in each drying chamber, one conveyer traveling in one direction and the other in the opposite direction; and means, at each end of the drier, for transferring a carrier for material from one chamber to the other. 125
